UNITED STATES PATENT OFFICE

WILLIAM W. GUEST, OF LOS ANGELES, CALIFORNIA

SHEAR PIN FOR CRUSHING MACHINES

Application filed December 6, 1930. Serial No. 500,576.

My invention relates generally to yielding jaw crushing machines of the type disclosed in my co-pending application for U.S. Letters Patent filed May 26, 1930, Serial No. 455,793 and the principal object of my invention is, to provide in a crushing machine of the type referred to, a shear pin that functions as a factor of safety in the event that the crushing machine is subjected to danger of injury or breakage in the event that a piece of metal or other uncrushable material accidentally enters the space between the crushing jaws.

Further objects of my invention are, to provide simple and efficient means for effecting the shearing of a pin at predetermined points in the event that an uncrushable object passes into the machine between the crushing jaws thereof, further, to arrange on the shear pin a toggle thrust sleeve that serves as a bearing for the toggle link or links that engage the pivoted or swinging jaw of the machine, further, to provide means whereby the thrust sleeve is adjustably mounted on the shear pin in order that new bearing surfaces may be presented to the toggle links in the event of wear by the said links and the surface of the thrust sleeve and further, to provide simple and efficient means for supporting the thrust sleeve and holding the same against rotation while serving as a thrust bearing for the toggle links.

A further object of my invention is, to provide saddles for the support of the toggle thrust sleeve on the frame of the crushing machine and which saddles are mounted so that they will by gravity, slide out of the frame of the machine in the event that the shear pin is sheared as a result of an uncrushable object entering the machine while the same is in operation.

A further object of my invention is, to provide a safety factor in the form of a shear pin for crushing machines that will effectually prevent distortion and breakage of the frame of the machine in the event that the crushing jaws encounter an uncrushable object.

With the foregoing and other objects in view, my invention consists in certain novel

features of construction and arrangement of parts that will hereinafter be more fully described and claimed and illustrated in the accompanying drawing in which:

Fig. 1 is a vertical section taken through the center of a yielding jaw rock crushing machine and showing the same equipped with a shear pin in accordance with my invention.

Fig. 2 is an enlarged cross section taken on the line 2—2 of Fig. 1.

Fig. 3 is an enlarged cross section of the shear pin and showing the end of the toggle link that engages the end of the thrust sleeve on said pin.

Referring by numerals to the accompanying drawing, which illustrates a practical embodiment of my invention, 10 designates the frame of a yielding jaw rock crushing machine, 11 the hopper through which the material to be crushed is fed into the machine, 12 the crushing jaw that is yieldingly resisted by spring cushion 13 and 14, the swinging jaw that is actuated by means of an eccentric 15.

Bearing against the upper rear portion of body 14 is the inner end of a toggle link 16.

Formed in the rear wall of the frame of the machine directly below the spring assembly that supports the upper portion of a jaw 14, is an opening 17 and projecting inwardly and upwardly from the lower portion of this opening is an inclined plate 18 that forms a part of the crusher frame.

Arranged for sliding movement on this plate 18, are saddles 19 that support a toggle thrust sleeve 20 and the latter encloses the intermediate portion of a shear pin 21.

This shear pin is preferably formed of mild steel and thrust sleeve 20 is formed of relatively hard metal, preferably treated steel.

The ends of thrust sleeve 20 terminate immediately adjacent to the inner faces of the side walls 10^a of the main frame 10 and seated in said side walls are shear pin bushings 22 of hardened metal that receive the end portions of the shear pin and the inner ends of these bushings abut the ends of the toggle thrust sleeve 20.

The ends of shear pin 21 project slightly

beyond the ends of the bushings 22 and said projecting ends are threaded for the reception of nuts 23 and which latter, when tightened, bear directly against the outer ends of 5 the thrust bushings.

Seated in and projecting from thrust sleeve 20, adjacent to the side walls 10^a are radially disposed pins 24, certain of which pins project into recesses that are formed in the outer 10 end of toggle link 16 and other pins project downwardly into recesses that are formed in the saddle blocks 19.

The pins that project into the toggle link 16 function as hinge pins at the same time 15 they retain the outer lower end of the toggle in position against the periphery of the thrust sleeve and those pins that project into the saddles 19, hold the toggle thrust sleeve against rotary movement.

20 As described, there are two sets of these pins 24 and each set comprises a plurality of pins, the same being radially disposed and preferably spaced equal distances apart. This arrangement enables the thrust sleeve 25 to be rotated a short distance so as to present a new bearing surface for the lower end of the toggle when one surface has become worn to an undesirable degree.

Obviously to make this adjustment of the 30 thrust sleeve, it is necessary to remove one of the nuts 13 and withdraw the shear pin and then rotate the thrust sleeve in one direction or the other so as to bring a new bearing surface into position to engage the outer 35 lower end of the toggle.

The end of the toggle link that bears 40 against the thrust sleeve is concave and its radius is slightly greater than the radius of the sleeve and, as a result of this construction, the toggle link while in operation, rolls on the surface of the thrust sleeve without sliding movement and therefore no lubrication at this bearing is required.

45 In the event that an uncrushable piece of material or a foreign object such as a dipper tooth enters the machine and passes downwardly between the jaws thereof, and which action would ordinarily damage the crusher to a considerable extent through breakage of 50 parts and distortion of the frame, the development of abnormal crushing strains produced as a result of the engagement of the jaws with the uncrushable object, will sheer the pin 21 on lines in the planes occupied by 55 the abutting ends of sleeve 20 and the bushings 22. When such shearing action takes place, the weight of the severed intermediate portion of the shear pin and the thrust sleeve, will cause the saddles 19 to slide by 60 gravity, downward over the inclined plate 18 and these parts will discharge through openings 17 in the wall of the frame.

65 This shearing action of the pin 21 at predetermined points, is effective in preventing distortion of the frame in which the pin is

normally supported and after a pin has been sheared it is a comparatively easy matter to install a new pin.

It will be understood that the abutting ends of the sleeve 20 and the bushings 22 70 provide shearing elements that act under abnormal pressure to shear the pin 21 at points just inside the side walls of the machine frame and thus said frame is in no wise damaged by breakage or distortion. 75

Thus it will be seen that I have provided a shear pin for yielding jaw rock crushing machines that is relatively simple in construction, inexpensive of manufacture, capable of being readily installed for use and very effective in performing the functions for 80 which it is intended.

It will be understood that minor changes in the size, form and construction of the various parts of my improved yielding jaw 85 rock crushing machine may be made and substituted for those herein shown and described without departing from the spirit of my invention, the scope of which is set forth 90 in the appended claims.

I claim as my invention:

1. In a yielding jaw rock crushing machine, bushings seated in the side walls of the machine, a shear pin having its end portions seated in said bushings and a toggle thrust sleeve arranged on said shear pin between said bushings, the ends of which sleeve and the inner faces of which bushings constitute shearing elements for cutting the shear pin in the event of abnormal pressures 100 thereupon.

2. In a yielding jaw rock crushing machine, bushings seated in the side walls of the machine, a shear pin having its end portions seated in said bushings, a toggle thrust sleeve arranged on said shear pin between said bushings and saddle blocks arranged for sliding movement on the frame of the machine and supporting said thrust sleeve. 105

3. In a yielding jaw rock crushing machine, bushings seated in the side walls of the machine, a shear pin having its end portions seated in said bushings, a toggle thrust sleeve arranged on said shear pin between said bushings the ends of which sleeve and the inner faces of which bushings constitute cooperating shearing elements for cutting the shear pin in the event of abnormal pressures thereupon and pins projecting from 115 said thrust sleeve.

4. In a yielding jaw rock crushing machine, bushings seated in the side walls of the frame of the machine, a shear pin having its ends seated in said bushings, a thrust sleeve arranged on said shear pin between said bushings the ends of which sleeve and the inner faces of which bushings constitute cooperating shearing elements for cutting the shear pin in the event of abnormal pressures thereupon, a toggle link bearing on said 125 130

thrust sleeve and hinge pins projecting from said thrust sleeve into said toggle link.

5. In a yielding jaw rock crushing machine, bushings seated in the side walls of the frame of the machine, a shear pin having its ends seated in said bushings, a thrust sleeve arranged on said shear pin between said bushings, a toggle link bearing on said thrust sleeve, hinge pins projecting from said thrust sleeve into said toggle link and the radius of the end of the toggle link that bears on said thrust sleeve being greater than the radius of said sleeve.
10. In a yielding jaw rock crushing machine, bushings located in the side walls of the machine, a shear pin having its ends seated in said bushings, a thrust sleeve mounted on said shear pin between said bushings, saddle blocks mounted for sliding movement on the frame of the machine below said thrust sleeve and pins projecting from said sleeve into said saddle blocks.

15. In a yielding jaw rock crushing machine, bushings seated in the side walls of the frame of the machine, a shear pin having its ends seated in said bushings, a toggle thrust sleeve arranged on said shear pin between said bushings and a plurality of pins seated in and projecting radially from said thrust

20. sleeve.
25. In a yielding jaw rock crushing machine, bushings seated in the side walls of the frame of the machine, a shear pin having its ends seated in said bushings, a toggle thrust sleeve arranged on said shear pin between said bushings, a plurality of pins seated in and projecting radially from said thrust

30. sleeve, a toggle bearing on said thrust sleeve and engaged by certain of said pins and saddle blocks arranged for sliding movement on the frame of the machine below said thrust sleeve and engaged by certain of the pins carried thereby.

35. In a yielding jaw rock crushing machine, bushings seated in the walls of the machine, a shear pin having its ends extended through said bushings and a toggle thrust sleeve adjustably mounted on said shear pin between said bushings.

40. 45. In a yielding jaw rock crushing machine, bushings seated in the walls of the machine, a shear pin having its ends extended through said bushings, a toggle thrust sleeve adjustably mounted on said shear pin between said bushings and toggle link engaging pins projecting radially from said thrust sleeve.

In testimony whereof I affix my signature.
WILLIAM W. GUEST.
